UNITED STATES PATENT OFFICE

117,154

DESIGN FOR A PHOTOGRAPHIC CAMERA OR SIMILAR ARTICLE

Oscar Steiner, Irondequoit, and Charles H. Roth,
Jr., Rochester, N. Y., assignors to The Folmer
Graflex Corporation, Rochester, N. Y., a cor-
poration of Delaware

Application December 31, 1938, Serial No. 82,110

Term of patent 14 years

To all whom it may concern:

Be it known that we, Oscar Steiner and Charles H. Roth, Jr., citizens of the United States, and residents respectively of Irondequoit and Rochester, county of Monroe, and State of New York, have invented a new, original, and ornamental Design for a Photographic Camera or Similar Article, of which the following is a specification, reference being had to the accompanying drawings, forming part thereof.

Fig. 1 is a side view of the photographic camera or similar article showing the range finder and shutter operating mechanism thereof;

Fig. 2 is a front view of the photographic camera or similar article closed and showing the range finder thereof;

Fig. 3 is a top plan view of the photographic camera or similar article showing the camera front open and the bellows partially extended, and the range finder; and

Fig. 4 is a rear perspective view of the photographic camera or similar article shown in Fig. 1 with the cable release omitted therefrom.

We claim:

The ornamental design for a photographic camera or similar article, substantially as shown and described.

OSCAR STEINER.
CHARLES H. ROTH, JR.
